[57] ABSTRACT

A glass cleaning device for use in a sink well filled with a washing solution is disclosed. The device includes a first guide member secured in an open-top receptacle, the guide member being formed of flexible fingers arranged in a cylindrical pattern. A cylindrically shaped sponge-like sleeve is fitted on the first guide member. A reciprocating cam assembly is arranged within the first sleeve such that when a small glass is pressed against it the fingers of the first sleeve are urged outwardly whereby the top portion of the sleeve contacts the glass while another part of the top portion of the sleeve contacts the outer edge of the glass. The device also includes a second guide member formed of cylindrically arranged flexible fingers with a hollow sponge-like sleeve arranged within the guide member and against the outer surface of the first sleeve. A large glass would be placed over the first sleeve which will contact the inner surface of the glass while the outer surface of the glass is contacted by the second sleeve. Should the outer dimension of the glass be greater than the inner diameter of the second guide member the fingers thereof would be flexed outwardly.

GLASS CLEANING DEVICE

BACKGROUND OF THE INVENTION

This invention relates generally to a drinking glass or receptacle cleaning device and more particularly to a cleaning device submerged in a sink or tub filled with a washing solution into which a glass, tumbler, cup, or the like is inserted and rotated or reciprocated by hand to clean the interior and exterior surfaces and rid the same of stains, such as lipstick marks, or the like.

Glass cleaning devices are well known and have their principle applications in business establishments such as restaurants, taverns, cafes, and the like. They provide the operator of such establishments with a quick convenience in cleaning glasses which have been used by customers, especially in those cases where only one individual is available to serve customers and at the same time must have on hand a ready supply of clean glasses for customer use. Wherever such glass cleaning devices are used it can be expected that a wide variety of differently sized and shaped glasses may be found. In a tavern, for example, the glasses would range from small whiskey glasses to large beer mugs having the usual handle on them. A problem has persisted in effectively cleaning all of the different shaped glasses with a single glass cleaning device. Some glass cleaning devices will not easily clean a large beer mug while others cannot effectively clean a small whiskey glass. In such cases the operator of the establishment must resort to alternative methods, such as hand scrubbing, to clean the odd sized, hard-to-clean glasses. Hand scrubbing is time consuming and inefficient. The alternative solution to cleaning the odd sized glasses could be to have several glass cleaning devices each designed to clean certain sized glasses. That alternative is undesirable because of the compact sizes of sinks generally found in taverns and restaurants and because of the expense in having multiple devices on hand.

In addition to their inability to clean odd sizes of glasses, the cleaning devices commonly used are ineffective in completely removing cigarette ashes or lipstick stains left on the surfaces of some cups or glasses. Various attempts have been made to remedy the stain removing problem but no widespread acceptable device has yet reached the market.

The present invention overcomes the above noted problems of existing glass cleaning devices and provides a device which by itself will effectively and efficiently clean any shape and size of glass commonly found in business establishments. Thus, a small whiskey glass to a large beer mug, and all shaped and sized glasses and cup in between are spotlessly cleaned by the device of this invention.

SUMMARY OF THE INVENTION

The present invention provides a glass cleaning device which, in its preferred form, includes a base member; an open-top cup-like receptacle secured at its bottom portion to the base member; a first upwardly extending hollow guide member secured in place with respect to the receptacle, the walls of the first guide member being constructed and arranged to flex outwardly when urged in that direction and to return to its original position when the urging force is removed; a cylindrically shaped first hollow sleeve formed of sponge-like material having a closed top and sized to fit snugly around a major portion of the first guide mem-

ber; urging means for urging the walls of the first guide member outwardly; the first guide member, first sleeve, and urging means being so constructed and arranged with respect to each other that when a glass is pushed downwardly on the urging means the walls of the first guide means flex outwardly carrying the first sleeve with it whereby a top portion of the first sleeve enters into the glass while another part of the top portion of the first sleeve contacts the outer edge of the glass and 5 the glass may be rotated to simultaneously clean its inside and edge portions; a second upwardly extending hollow guide member secured in place with respect to the receptacle and spaced radially outwardly of the first guide member to define an annular space therebetween, the walls of the second guide member being constructed and arranged to flex outwardly when urged in that direction and to return to its original position when the urging force is removed; a cylindrically shaped second hollow sleeve formed of a sponge-like 10 material sized to fit snugly within the second guide member and against the outer surface of the first sleeve; and the second guide member and second sleeve being so constructed and arranged with respect to each that when a glass is placed over the first sleeve 15 20 25 30 35 40 45 50 55 60 65 70 75 80 85 90 95 100

the inner portion of the glass is contacted by the outer surface of the first sleeve while the outer portion of the glass is contacted by the inner surface of the second sleeve and the wall of the second guide member is flexed outwardly should the glass being washed be greater in size than the inner diameter of the second guide member.

In the preferred form of the invention both the first and second guide members are formed of separated fingers arranged in a generally cylindrical pattern. An upwardly urged cam assembly is disposed within the first guide member to urge the fingers outwardly when a small glass, such as a whiskey glass, is pushed down on the cam. When a large glass, such as a beer mug, is to be cleaned it is pushed down over the first sleeve and the handle of the mug pushes out the fingers of the second or outer guide member. Also in its preferred form, the elements of the invention are interconnected in such a manner as to allow easy disassembly and assembly of the device.

Various other advantages, details and modifications of the present invention will become apparent as the following description of a present preferred embodiment thereof proceeds.

BRIEF DESCRIPTION OF THE DRAWINGS

In the accompanying drawings I have shown a present preferred embodiment of the present invention in which:

FIG. 1 is an elevation view in cross-section of a preferred embodiment of the present invention;

FIGS. 2a and 2b are perspective views showing the elements of the device of FIG. 1 detached from each other;

FIG. 3 is a perspective view of the first guide member forming part of the present invention showing the outward movement of the fingers resulting from the downward urging of the cam assembly;

FIG. 4 is an elevation view in cross-section of the first guide member together with the first sleeve and a small glass being urged downwardly on the cam assembly;

FIG. 5 is a perspective view of the second guide member and second sleeve forming part of the present

invention and a beer mug being urged downwardly with one of the fingers of the second guide member being urged outwardly; and

FIG. 6 is a partial elevational view in cross-section showing certain of the elements of the present invention co-acting to clean a beer mug.

Referring now to the drawings, there is shown in FIG. 1 the assembled view of the glass cleaning device 10 embodying the present invention. The device 10 includes a base member 12 having an annular shape with four slotted openings 14 disposed 90 degrees of each other and used for discharging water therethrough when the device 10 is immersed in a sink basin of water and cleaning solution. The bottom of the base member 12 is shaped to receive a suction cup member 16 which includes a plurality of regularly spaced suction cups which serve to fix the device 10 onto the flat surface such as a sink bottom. The suction cup member 16 is secured to the base member 12 by any suitable means such as by fixing it with an adhesive. A cup shaped, flared top receptacle 18 is snugly fitted into the base member 12. The bottom of the receptacle 18 is generally closed with a center opening 19 shaped to receive a key lock, to be described later, four slotted openings 20 of the same size as the opening 14 in the base member 12 with the openings 20 and 14 being aligned during assembly of the device 10 for water to flow when the device is immersed during use.

A first guide member 24 is arranged centrally of the receptacle 18 and is formed of a plurality of elongated fingers 25 secured in a pivotable manner at their lower ends to a lower cup-shaped annular section 26, the fingers 25 forming a cylindrical pattern are constructed and arranged to be urged radially outwardly into a frusta-conical pattern as shown in FIGS. 3 and 4. Each of the fingers 25 has a radially inwardly extending cam follower 27 formed thereon and shaped and sized to be engaged by a disc-shaped cam 28 forming part of a cam assembly 29 arranged within the confines of the first guide member 24. A downwardly extending shaft 30 is fixed to the underside of the cam 28 and is sized to fit in a slidable relationship into a cylinder 32 secured to the bottom surface 33 of the first guide member 24. As shown in FIG. 1 the cam assembly 29 is urged upwardly by a helical coil spring 34 arranged in the bottom of cylinder 32 to engage the bottom of shaft 30. The spring 34 urges the cam assembly 29 to a point where the cam 28 is above the cam followers 27. The material used in the construction of the first guide member 24 should have a resiliency characteristic to permit the fingers 25 to return to the cylindrical pattern whenever the cam 28 is returned to its neutral position as shown in FIG. 1. The cylinder 32 extends through the bottom of annular section 26 with the lower end being generally closed except for a drainage opening 35 provided therethrough and having a pair of radially extending diametrically opposed tabs 34' secured thereto. The tabs 34' and outer diameter of the cylinder 32 are sized to fit into the slotted opening 19 provided in the bottom of receptacle 18. When assembling the first guide member 24, the cylinder 32 is aligned with opening 19, placed therethrough and rotated so that the tabs 34 are displaced away from the slots of opening 19. The first guide member 24 is thereby fixed with respect to the receptacle 18. The first guide member 24 is secured in place by means of a pressure disc 37 fitted into a centrally located bore 36 formed in the top surface of the

suction cup member 16. The material of the suction cup member 16 is of a resilient nature and the disc 37 is arranged and sized to bias the first guide member 24 upwardly by acting on the end of the cylinder 32. To disassemble the guide member 24 from the receptacle 18, the guide member is pushed downwardly whereby the disc 37 acts against the resilient material of the suction cup member 16 to overcome the locking force, the guide member rotated to align the tabs 34 with the slots of opening 19 and the guide member lifted out.

The cam assembly 29 is also provided with an upwardly extending stem 38 centrally secured to the upper surface of the cam 28 and sized to engage the inner surface of a hollow, generally cylindrically shaped first sleeve 40 which in turn is sized to fit snugly on the outside surfaces of the fingers 25 of the first guide member 24, as shown clearly in FIGS. 1 and 4. The sleeve 40 is formed from a sponge like material suitable for acting against a glass surface to clean it, and is longitudinally sized to reach downwardly to the annular section 26 of the first guide member 24 which may be provided a band of locking material 41 such as Velcro material, secured to its outer surface for holding the sleeve 40 in place to the guide member 24 while at the same time permitting the sleeve to be easily removed if desired. The outer diameter of the sleeve 40 is of such a dimension as to be sufficient to engage the inner surface of glass so that cleaning action by the sleeve may be transmitted to the glass, as shown by way of example in FIG. 6. A second guide member 44 is arranged centrally of the receptacle 18 and is formed of a plurality of elongated fingers 45 secured in a pivotable manner at their lower ends to a lower cup-shaped annular section 46 integral with a flat bottom section 47 having a slotted opening 48 through the center thereof shaped and located to align with the slotted opening 19 of receptacle 18 for receiving the tab 34' and bottom portion of cylinder 32 of the first guide member 24. The fingers 45 are arranged in a generally cylindrical pattern with a radially outwardly flare at the mouth or upper end. Four slots 51 spaced 90 degrees apart are provided in bottom section 47 and annular section 46 for drainage purposes and are arranged to align with the drainage openings 14 of the base member 10 and slotted openings 20 of the receptacle 18. The material used in the construction of the second guide member 44 should have a resiliency characteristic to permit the fingers 45 to return their original cylindrical pattern whenever a flexing force such as would be applied by a large glass, as shown in FIGS. 5 and 6, is removed. The flare configuration of the mouth of the second guide member 44 permits ease of emplacement of a large glass into the guide member. The inner diameter of the second guide member 44 is of such a dimension as to form a space with the sleeve 40 sufficient to accommodate another glass cleaning sleeve as described below.

A hollow, generally cylindrical, open ended sleeve 50 formed from a sponge-like material is removably received in the second guide member 44 and is sized to fit snugly against the inside wall surfaces of the fingers 45, as shown in FIG. 1. The upper portion of the sleeve 50 overlaps the fingers 45 and extends downwardly to an intermediate position of the outer surfaces of the fingers. As shown in FIG. 1, the sleeve 50 extends to the bottom of the inside surfaces of the annular section 46. The thickness of the sleeve 50 is such that the inner

surface of the portion within the guide member 44 abuts the lower outer section of the first sleeve 40. The elasticity of the sleeves 40 and 50 and the sizes of the first guide member 24 and second guide member 44 are such to permit a glass to be placed over the first guide member 24 and sleeve 40, as shown in FIGS. 5 and 6, and within the confines of the second guide member 44 and to permit rotation or reciprocation of the glass to thereby clean the glass.

A pair of self threading screws 60 serves to hold the base member 12, receptacle 18, and second guide member 44 together. Suitable holes are provided through the suction cup member 16, receptacle 18 and second guide member 44 to accept the screws 60.

FIGS. 3 and 4 show the action of the cam assembly 29, fingers 25, and first sleeve 40 when a small glass such as the whiskey glass illustrated is to be cleaned by the device of the present invention. The glass is placed centrally of the sleeve 40 and urged downwardly so that the inner bottom of the glass presses on the stem 38 to urge the cam 28 downwardly to engage the cam followers 27 and thereby urge the fingers 25 outwardly as shown. The lip section of the glass enters within the confines of the first guide member 24 and is engaged by an upper surface section of the sleeve 40 while the entire inner surface of the glass is engaged by another section of the top of the sleeve 40. The glass may then be rotated to clean the interior and the outer section around the lip.

It should now be clearly understood how the advantages of the present invention as specified in the introductory portion of this specification are achieved. In addition to that it is to be noted that the elements comprising the glass cleaning device of this invention may be easily disassembled from each other simply by removing the screws 60 and twisting the first guide member 24 into its unlocked position as previously described. Assembling the elements is equally simple. Also, the elements may be constructed so that essentially they are separate from each other so that should one element be damaged only that element need be replaced rather than the entire device. It should also be noted that the cleaning sleeves are easily removed for replacement or cleaning without the need for disassembling the supporting elements or even removing the device from a sink. Finally, it is to be emphasized that the glass cleaning device of this invention has been proven to clean glasses found in business establishments in an efficient and effective manner.

While I have shown and described a present preferred embodiment of this invention, it is to be distinctly understood that the invention is not limited thereto, but may be otherwise variously embodied within the scope of the following claims.

I claim:

1. A glass cleaning device comprising:
a base;
an open-top cup-like receptacle secured at its bottom portion to said base;
a first upwardly extending, hollow guide member secured in place with respect to said receptacle, the walls of said first guide member being constructed and arranged to flex outwardly when urged in that direction and to return to its original position when the urging force is removed;

a first hollow sleeve formed of sponge-like material having a closed top and sized to fit snugly around a major portion of said first guide member; urging means for urging the walls of said first guide member outwardly;

said first guide member, first sleeve, and urging means being so constructed and arranged with respect to each other that when a glass is pushed downwardly on said urging means the walls of said first guide means flex outwardly carrying the first sleeve with it whereby a top portion of the first sleeve enters into the glass while another part of the top portion of the first sleeve contacts the outer edge of the glass and the glass may be rotated to simultaneously clean its inside and edge portions; a second upwardly extending hollow guide member secured in place with respect to said receptacle and spaced radially outwardly of the first guide member to define an annular space therebetween, the wall of said second guide member being constructed and arranged to flex outwardly when urged in that direction and to return to its original position when the urging force is removed;

a second hollow sleeve formed of a sponge-like material sized to fit snugly within the second guide member and against the outer surface of said first sleeve; and

said second guide member and second sleeve being so constructed and arranged with respect to each other that when a larger glass is placed over said first sleeve the inner portion of the glass is contacted by the outer surface of said first sleeve while the outer portion of the glass is contacted by the inner surface of the second sleeve and the wall of the second guide member is flexed outwardly should the glass being washed be greater in size than the inner diameter of the second guide member.

2. A glass cleaning device as set forth in claim 1 including suction means secured to the bottom of said base in a fixed relationship with a flat surface.

3. A glass cleaning device as set forth in claim 1 wherein said first guide member is formed of a plurality of separated fingers, each being pivotally connected at its bottom end to a ring-shaped section of the first guide member.

4. A glass cleaning device as set forth in claim 1 including securing means for holding said first sleeve in a fixed position on said first guide member.

5. A glass cleaning device as set forth in claim 1 wherein said second sleeve is sized to extend down along a major portion of the inner surface of said second guide member and to fold over the top edge of said second guide member to extend downwardly to an intermediate position of the outer surface of said second guide member.

6. A glass cleaning device as set forth in claim 1 wherein the upper section of said second guide member is flared radially outwardly.

7. A glass cleaning device as set forth in claim 1 wherein said second sleeve has cylindrical shape and said second guide member also has a cylindrical shape.

8. A glass cleaning device as set forth in claim 1 wherein said second guide member is formed of a plurality of separated fingers, each being pivotally connected at its bottom end to a ring-shaped section of the second guide member.

9. A glass cleaning device as set forth in claim 3 wherein each of said fingers includes a cam follower on the inside surface thereof; and wherein said urging means includes an upwardly and downwardly reciprocating cam member arranged to simultaneously engage each of said cam followers, and biasing means urging said cam member in an upwardly direction.

10. A glass cleaning device as set forth in claim 1 including locking means for detachably locking said first guide member to said receptacle.

11. A glass cleaning device as set forth in claim 1 wherein said urging means includes an upwardly extending stem member arranged to engage the top portion of the first sleeve and to extend to a point adjacent the bottom of the inner portion of a glass whereby the top portion of said first sleeve will be forced into the inner surface of a glass pushed downwardly on said stem.

* * * * *
